UNITED STATES PATENT OFFICE.

JOHN WHITAKER, OF NORTH WALES, PENNSYLVANIA, ASSIGNOR TO SAFE-GUARD
CHECK WRITER COMPANY, INC., OF LANSDALE, PENNSYLVANIA, A CORPORA-
TION OF PENNSYLVANIA.

CHECK.

1,803,434.

Specification of Letters Patent. Patented May 13, 1919.

Application filed January 8, 1917. Serial No. 141,390.

To all whom it may concern:

Be it known that I, JOHN WHITAKER, a citizen of the United States, and a resident of North Wales, county of Montgomery, 5 State of Pennsylvania, have invented certain Improvements in Checks, of which the following is a specification.

One object of my invention is to arrange the characters representing the amount of a 10 check in such a manner that the words can be printed in full without increasing the space occupied by the amount and large characters may be used.

A further object of the invention is to arrange the words so that it will be difficult to change any of the words:

A still further object of the invention is to carry the perforations not only through the amount, but also through the line on 20 which the payee's name has been previously written or printed.

These objects I attain in the following manner, reference being had to the accompanying drawings in which:

25 Figure 1 is a face view of a check filled out with the characters representing the amount printed thereon;

Fig. 2 is an enlarged view of the printed line showing the perforations, and

30 Fig. 3 is a diagrammatic sectional view through a portion of the check illustrating the perforations made by separating the fibers.

a is the check of the usual size having, in 35 the present instance, a line for the payee's name and a line for the amount for which the check is to be printed. The printed matter indicating the amount fills the space between these lines, as clearly shown in the 40 drawings. In the drawings, the check has been drawn for one hundred and thirty dollars and fifty cents and each word is on a separate diagonal line. The lines are spaced an equal distance apart so that one word 45 underlaps the preceding one. At each end of each word b, Fig. 2, is a closing character c. This character may be of different lengths according to the length of the word. If the word is a short one, then this character is longer than if the word were a long 50 one. For instance, the character c for the word "one" is much longer than the character c for the word "hundred." By this arrangement, the lines are of the same length 55 and fill the space between the two lines d

and e of the check. I preferably close the ends of the full lines by any suitable characters f. Two sets of diamond shaped figures are shown in the present instance. The words, as well as the characters, may be 60 perforated simultaneously with the printing and the perforation, in the present instance, is accomplished by teeth which are forced through the back of the check, the teeth having a certain amount of lateral movement 65 so as to open the fibers of the check without materially interfering with the printed surface so that the surface printed is substantially solid and easily read, but the paper is destroyed to such an extent that it 70 is almost impossible to erase a word, or a letter of a word, and to insert another in its place.

I preferably extend the perforations beyond the character representing the amount 75 of the check so that they will perforate the line occupied by the payee's name, and if the payee's name be written as illustrated in Fig. 1, or printed on a typewriter, or other machine, before the amount is printed, the 80 teeth, which enter the paper, will separate the fibers so as to make it exceedingly difficult to change the name. As hereinbefore stated, the separation of the fibers is such as not to destroy materially the face of the 85 check, so that the payee's name is legible.

By arranging the words denoting the amount of a check on an incline and arranging them so closely together that one will underlap another, I am enabled to 90 print the words for a larger amount without increasing the check beyond the normal size. This cannot be accomplished on a single line in any other manner.

By arranging the lines diagonally and 95 spacing the lines a given distance apart, I am enabled to dispense with the intricate changeable feed for each character, now used in machines in which the characters are arranged in a straight line, as the words of 100 each line can be of any length without interfering with the feed, the feed being transverse to the line instead of parallel with it. Consequently, each line is spaced a given distance apart and a simple feed can be 105 used.

Furthermore, by arranging the lines diagonally and placing one word only on a line, I am enabled to increase the size of the letters of the words and particularly their 110

width, also the space between the letters, so as to render the printed matter legible. This cannot be done in machines where the characters are placed on a single line without 5 making a very long check, which would not be acceptable to the banks.

While I have shown the serrating of the paper on the line of the payee's name without ink, any suitable solution may be used 10 that would not obliterate the name but would be affected by acid or other erasive matter.

I claim:

1. A check having two longitudinal spaces, 15 one for the payee's name and one for the amount of the check, the amount of the check being printed thereon in words arranged on diagonal lines, the paper beneath the above printed matter having the fibers

separated at close intervals, the separation 20 of the fibers extending beyond the printed matter and into the space occupied by the payee's name.

2. A check having a longitudinal space for the payee's name and a longitudinal 25 space directly below the first mentioned space for the amount of the check, the amount of the check being printed in the last mentioned space in words arranged on diagonal lines spaced apart, one line underlapping a preceding line, the paper beneath the above printed matter having the fibers separated at close intervals, the separation 30 of the fibers extending beyond the printed matter and into the space occupied by the payee's name.

In witness whereof I affix my signature.
JOHN WHITAKER.
